UNITED STATES PATENT OFFICE.

OLAF N. GULDLIN, OF FORT WAYNE, INDIANA.

APPARATUS FOR MAKING GAS.

SPECIFICATION forming part of Letters Patent No. 790,296, dated May 23, 1905.

Application filed July 31, 1902. Serial No. 117,888.

To all whom it may concern:

Be it known that I, OLAF N. GULDLIN, a citizen of the United States, residing at Fort Wayne, in the county of Allen and State of Indiana, have invented certain new and useful Improvements in Apparatus for Making Gas; and I do hereby declare the following to be a full, clear, and exact description of the invention, such as will enable others skilled in the art to which it appertains to make and use the same.

This invention relates to apparatus for manufacturing illuminating water-gas comprising a generator, a carbureter, and a fixing-chamber or superheater and to certain improved features of construction in the carbureter.

The object of my invention is to provide for more evenly and quickly heating the fuel to incandescence in the generator and more effectively decomposing steam, resulting in an increased percentage of carbonic oxid and a corresponding decreased percentage of carbonic acid in the water-gas. By the use of my divided air-blast at higher pressure or in larger volume more complete and uniform combustion of the fuel is effected, much more rapidly heating and restoring the same to incandescence down to the grate-bars. The producer-gas while passing off from the generator at a high heat does not contain so large a per cent. of combustible gas, for the reason that such gas has been burned in the body of fuel, highly and uniformly heating the same for more effectively decomposing the steam which is subsequently admitted.

Another object of my invention is to provide an extended height of carbureting and fixing chambers containing a greater extent of heating-surfaces, so that such surfaces may be of a comparatively lower temperature—that is, a dull red heat—for converting the oil-vapors by longer exposure into heavy carbureted hydrogen gas of high candle-power without loss of illuminants in the form of lampblack or hard carbon or formation of marsh-gas.

Another object is to provide for better arresting and removing ashes in the pipe and flue connection between the generator and the carbureter; also, for better carrying the oil-vapors from the vaporizing and mixing cham-

ber down into the fixing-chamber containing checker-bricks, where they are combined with the water-gas to make fixed illuminating-gas.

In raising the heat in the generator—that is, heating the body of fuel to incandescence—
55 it has heretofore been the common practice to admit the air-blast through a pipe at one side of the generator or ash-pit, resulting in the blast striking on the opposite side of the ash-pit and crowding the fire on that side
60 of the generator or in finding weak uneven spots in the bed of fuel and forming channels or chimneys along the wall or through the body of fuel, leaving other portions of the fuel insufficiently burned and heated and making an uneven fire. As a result of this defective heating operation the steam when admitted escapes through said channels or cooler part of fuel-bed without thorough decomposition, resulting in an excess of deleterious
65 carbonic acid instead of the desirable carbonic acid which should be made to the exclusion of carbonic acid when making water-gas. Owing to these difficulties and other causes a
70 comparatively low blast-pressure, usually from twelve to sixteen inches, has been carried, whereas by my method a high air-pressure of from twenty to twenty-four inches or more can be carried by means of my divided jets directed to strike in between adjacent grate-bars, and more complete and uniform combustion of the fuel is effected, more rapidly heating the same, making a smaller per cent.
75 of carbonic oxid and a larger per cent. of carbonic acid, and materially increasing the capacity of the apparatus.
80

By my improved method of operation and features of construction the defects and difficulties above mentioned are overcome and greatly improved results secured.
85

My improved apparatus is illustrated in the accompanying drawings, in which—
90

Figure 1 represents a vertical section, partly in elevation, of the apparatus. Fig. 2 represents a horizontal section of the same on the irregular line 2 2, Fig. 1. Fig. 3 represents a vertical section showing a modification of the pipe connection and uptake-flue in the carbureter. Fig. 4 represents a horizontal section on line 4 4, Fig. 3. Fig. 5 represents
95 100

a sectional detail view showing ports for admitting gas and air into the upper part of the vaporizing-compartment.

The gas-generating furnace A is constructed of an iron shell and a fire-brick lining in the usual manner and is provided at the top with a fuel-opening *a*, closed by a lid *x* and fastening device *x'* and at the bottom by the usual ash and clinker openings *a'* and *a''*, which in practice will be closed by suitable doors. A steam-supply pipe *S*, having a valve, connects with the top of the generator through a cast iron or steel box *w*, secured in the fire-brick arch, as shown, and another valved steam-pipe, *S'*, connects with the ash-pit, either directly or through the blast-pipe *J*. The box *w* serves to deflect the steam downward without injury to the brickwork. The gas-outlet pipes *B* and *C* connect, respectively, at top and bottom of the generator and are in practice each provided with a valve-box like the box *B'* shown at the top. The gas-outlet pipes *B* and *C* connect, through the delivery-pipe *B''*, with the uptake-flue *D'*, or pipe *C* may connect directly with flue *D'*, which is connected with the vaporizing and mixing compartment *E* of the carburetor *D*. The valve-box *B'* is connected between the gas-outlet pipe *B* and the delivery-pipe *B''* and is preferably provided with an annular hollow seat *g* for the ball-valve *f*; but this special form of valve-box and valve may be omitted.

At one side of carburetor *D* is constructed the brick-lined uptake-flue *D'*, having connecting with its lower end the ash-receiving chamber or pocket *B''*, closed at the bottom by a tight-fitting door *b* and fastening device *y*. The gas-pipes, valve-box, ash-chamber, and uptake-flue are preferably lined with fire-brick, as shown.

To the ball-valve *f* is connected the rod *h*, to which in turn is connected the rack-bar *h'*, which extends up into the valve-stand *H*, where it is engaged by a pinion (not here shown) having a hand-wheel *G*, supported at the top of the stand. These devices are described and covered by claims in my Patent No. 644,511, dated February 27, 1900.

The uptake-flue *D'*, Figs. 1 and 3, connects by opening *d* with the lower part and by the smaller opening *d'* or *d''* with the upper part of the oil vaporizing and mixing compartment *E* of the carburetor *D*, so that water-gas may be intimately mixed with the oil-vapors. This flue *D'* serves as an arresting and deposit chamber for ashes and cinders, which are precipitated therein and deposited in the ash-pocket *B''* at the lower end thereof, so that they may not pass into and clog the passages and compartments in the carbureting and fixing chamber *D*. This is an improved and additional feature of construction in the pipe and valve connection and ash-receiving chamber described and claimed in my Patent No. 644,511 and has given improved results.

The carburetor *D* and the superheater *F* are made of extended or increased height as compared with the generator and with such chambers as heretofore made for providing an increased extent of heating-surface—brick checker-work—so that the hydrocarbon vapor and gas may be combined with the water-gas and made into fixed illuminating-gas at a lower temperature, resulting in a saving of valuable illuminants, which would otherwise be deposited as lampblack or form marsh-gas by overheating of the hydrocarbons. The carburetor *D* is constructed with an open brick arch near the bottom for supporting the checker-work in the fixing-chamber *E'* and forming a bottom gas-chamber. The oil vaporizing and mixing compartment *E* extends from the brick checker-work to the top of the carburetor and serves for vaporizing hydrocarbon oil and thoroughly mixing it with water-gas. Oil-supply pipes or injectors *e'* are preferably placed in the wall of compartment *E*, but may be otherwise located for supplying oil spray or vapors to be mixed with the water-gas admitted through passages *d* and *d'*, Fig. 1, or ports *d''*. (Shown in Figs. 3 and 5.)

Air is admitted through suitable ports *e''* into the vaporizing and mixing compartment *E*, Fig. 1, for burning the producer-gas admitted through opening *d*, *d'*, or *d''* for heating the brick checker-work in the fixing-compartment *E'* below. Air may also be admitted into other parts of chamber *D*—for instance, as shown in Figs. 3 and 4—and into various parts of the superheater *F*, where required, for burning the producer-gas and heating the brick checker-work to the desired temperature. The lower end of chamber *D* is connected by pipe *f'* to the lower end of superheater *F*. The superheater is constructed with a bottom brick arch and brick checker-work above in a well-known manner and is provided at the top with a short smoke-stack *o*, having a tight-fitting lid *o'*. The gas-take-off pipe *o''* connects with stack *o* and extends down into a seal-box, (not here shown,) but preferably located on top of the charging-floor.

Suitable sight-openings *t* connect, as shown in Fig. 1, with the top of carburetor *D* and with the upper end of flue *D'* for inspecting the interior and ascertaining the condition of the heat.

The air-blast box *K*, Fig. 2, is preferably placed in the brick lining of the generator at about the grate-level and has secured to it the desired number of perforated air-distributing pipes *L*, which are preferably arranged and supported in such manner that they will not obstruct the ash-chamber *V*. The free ends of pipes *L* may rest upon the cast-iron shoes or brackets *P*, permitting expansion and contraction under changes of temperature. The pipes *L* are provided with lateral ports *m* and at the top with notches or other spacing de-

5 vices l'' , arranged in lines between said ports for receiving the grate-bars, (not here shown,) so that jets of air may be discharged from the ports between adjacent grate-bars directly into the body of fuel. The details of construction and arrangement of these blast-distributing pipes are fully illustrated, described, and claimed in my Patent No. 721,695, dated March 3, 1903. An air-blast pipe J connects 10 with the box K and has a controlling-valve j . I have provided, in addition to the pipe and valve connection and ash-receiving chamber described and claimed in my Patent No. 644,511, the uptake-flue D', Figs. 1 and 3, for 15 better arresting ash and cinder. The vertical wall of this flue opposite the end of the horizontal pipe B² serves as a baffle-plate for the impinging gases discharged by said pipe, causing the accompanying dust and ashes to 20 be arrested and deposited in the pocket B³. This has proved to be an important feature in practice, since it prevents the checker-brick in the carbureting-chamber from becoming clogged with hard deposits of ash and 25 tar or hard carbon, and thus becoming inoperative.

Instead of constructing the uptake-flue D' on the outside of the carbureter D entirely independent or connected to same, as shown 30 in Figs. 1 and 2, I may construct such flue of special tiles within the cylindrical shell, as shown in Figs. 3 and 4. The lower end of the flue in this arrangement is inclined downward and outward to the ash-receiving chamber B³, so that the ashes arrested will slide 35 down into such receiving-chamber. The flue D' extends up inside of the cylindrical shell to the inwardly-projecting tile e and is provided with a horizontal opening d for admitting 40 gas and air into the compartment E. Ports d'', Figs. 3 and 5, are provided for permitting part of the water-gas and blast-gases to pass into the upper part of compartment E. An air-blast box I is secured to the iron 45 shell at the upper end of the flue D' and connects by opening e'' with flue D'. An air-blast pipe J' connects with box I, so as to be controlled by a valve i. Air when admitted to the blast-box passes through opening e'' and mixes with the producer-gas passing up 50 through flue D', and the mixture passes through opening d into compartment E, where combustion takes place. The shell of the delivery-pipe B² and the ash-pocket B³ may be 55 made in one piece with a flange which is bolted directly to the shell of chamber D.

A separate pipe (not here shown) may connect with the ash-pit and the valve-chamber for conducting water-gas to the carbureter D instead of passing it out through the blast-box and connection. (Shown in Fig. 1.)

The operation of making gas may be conducted as follows: A fire is kindled on the grate and fed with fuel, which is heated to 65 incandescence in the usual manner; but the

air-blast is admitted to the blast-box K at a high pressure up to twenty-four inches or even higher or in materially increased volume and is discharged in jets between the adjacent grate-bars, causing complete, rapid, 70 and even combustion of the fuel close down to grate-bars and also so that a deep body thereof is uniformly heated to incandescence in much less time than formerly. The blast-gases are passed through the pipe connections, 75 uptake-flue D', and openings d d', Fig. 1, or opening d and ports d d'', Fig. 3, into the carbureting-chamber, where the combustible gases are burned by jets of air admitted through ports e'' or e'''. The hot products of 80 combustion and unconsumed gases pass down through the checker-work in chamber D and thence into superheater F. Air is admitted where required for completely burning the 85 gases and heating the checker-work to the desired temperature. The waste products finally escape through the stack o, the lid of which is open. The oil vaporizing and mixing compartment E is partly heated by radiant heat and partly by the burning of blast-gases. 90 Some of the air-ports e'', Fig. 1, may be inclined upward for directing streams of air upward for that purpose. The body of fuel having been heated to incandescence and the chambers D and F heated to the desired temperature, the air-blasts are shut off, lid o' closed, and water-gas is generated by admitting steam into the base of the generator. Rapid and uniform decomposition of steam is thus effected, producing hydrogen and carbon monoxid, with material reduction of 95 carbonic acid, and permitting longer periods of gas-making, which, with the shorter periods of blast, effects a large increase in capacity of the apparatus. Steam having been passed 100 into the body of fuel, oil is sprayed by the injectors e into the vaporizing and mixing compartment E. As the hot water-gas rises through flue D' it passes through passage d and d' into compartment E, where it mixes with 105 the oil-vapors and carries them down into contact with the hot checker-brick in compartment E', where the gases and vapors are completely combined and then converted into fixed illuminating-gas in passing through the 110 checker-work in chamber F. The gas finally passes off through pipe o'' to the usual seal-box and thence to the washer and scrubber. (Not here shown.) The hydrocarbon vapors 115 passing down into compartment E' are enveloped by the water-gas, which enters through opening d, so that the hydrocarbon illuminants will not be destructively decomposed into marsh-gas or deposited as lamp-black and hard carbon on the checker-brick. 120 After the gas-making run is completed and the apparatus again heated up, as above described, a reverse or down run can be made if steam is admitted through pipe S at the top 125 of the generator and passed down through 130

the incandescent fuel, where decomposition is effected. The resulting water-gas passes off through pipe C and uptake-flue D' into the carbureter D.

5 Having described my invention, what I claim, and desire to secure by Letters Patent, is—

1. The combination with a gas-generator of a carbureter having at the top an oil vaporizing and mixing compartment provided with an air-inlet and a fixing-compartment below, an uptake-flue having openings at the upper end into said vaporizing and mixing compartment, and a pipe connection from the generator into said flue, substantially as described. 40

2. The combination with the gas-generator of a carbureter, having a vaporizing and mixing compartment, a gas uptake-flue at one side of the carbureter and having an opening into said compartment, and an air-blast opening, communicating with said flue whereby the air-blast may be directed into, and mixed with the ascending gas and discharged into the vaporizing and mixing compartment, 45 and a pipe connection from the generator to the uptake-flue, substantially as described. 50

3. In a gas-generating apparatus, the carbureting-chamber having a lateral gas uptake-flue, inwardly-projecting tile above said flue, an upper oil vaporizing and mixing compartment and a lower fixing-compartment, said flue having a lateral discharge-opening and one or more ports opening into the vaporizing-compartment, substantially as described. 55

35 4. The combination with the gas-generator

and the carbureting-chamber, of the gas uptake-flue at one side thereof and having an opening into said chamber and an opposite air-blast opening, a blast-box secured to the outer wall of said flue and connecting therewith through said blast-opening, whereby the air-blast may be directed into, and mixed with the ascending gas and discharged into the carbureting-chamber, and a pipe connection from the generator to the uptake-flue, 45 substantially as described. 55

5. In a gas-generating apparatus, the carbureter having an upper oil vaporizing and mixing compartment and a lower fixing-compartment, a lateral gas uptake-flue having a lateral discharge-opening above the lower compartment and one or more ports opening into the upper compartment, and inwardly-projecting tile above said flue, substantially as described. 60

6. The combination with a gas-generator of a carbureter having at the top an oil vaporizing and mixing compartment and a fixing-compartment below, an uptake-flue having openings at the upper end into said vaporizing and mixing compartment, and a pipe connection from below the grate into said uptake-flue, substantially as described. 65

In testimony whereof I affix my signature in presence of two witnesses.

OLAF N. GULDLIN.
